UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 18, 1923. Serial No. 663,369.

This invention relates to telephone exchange systems and more particularly to a system in which connections are established between telephone lines by means of automatic switching apparatus.

The object of this invention is to provide an improved impulse circuit for setting the automatic selector switches in systems of this character.

19 The invention will be more readily understood by referring to the accompanying drawings, Figs. 1 and 2 and the more detailed description which follows:

In accordance with this invention a source 15 of alternating current, preferably within the voice range, is provided at the central office, which upon the initiation of a call on any telephone line is connected in a circuit including the impulse dial at the substation.

20 An alternating current relay at the central office, which responds to the impulses produced by the dial, repeats these impulses into a direct current circuit including a direct current impulse relay which controls 25 the setting of the (numerical) switches to connect with the desired line.

Fig. 1 represents the called station and the usual train of selector switches and a portion of a trunk circuit through which 30 these switches are approached. Fig. 2 represents the remainder of this trunk circuit, a line finder connected thereto and a calling subscriber's station, also a trunk finder, and an impulse repeater connected thereto. This 35 invention may be applied to any telephone system employing automatic or mechanical switching devices, but for purposes of explanation in this application it is applied to, and described in connection with, the well known Strowger system such as is described 40 in the patent to A. H. Blessing, No. 1,176,269, March 21, 1916. The selector switches S and S¹, Fig. 1, may be of the type of the switch shown at E¹, and the connector C of the 45 type of the switch I, both shown in Fig. 2 of the Blessing patent. The apparatus shown at "R" Fig. 1, is part of the repeater circuit and will be described hereinafter in greater detail.

50 In general, the system functions in the following manner.

One station desiring to communicate with another removes the receiver from the switchhook thus causing certain circuits to func-

tion and connect a combined repeater and selector circuit to the calling line. The repeater circuit which is supplied with alternating current preferably of a frequency and magnitude within the voice range is capable of being associated with a selector 55 switch of the well known Strowger type. When the calling station dials, the repeater responding to the impulses of alternating current produced, reproduces the train of impulses to energize the selector switch causing 60 it to step to the proper level, trunk hunt, and connect with an idle selector switch in the succeeding trunk group in the manner well known in the art. The repeater now 65 controls the operation of the succeeding selector switches of the train in the same manner, until the connection is extended to the desired called line when the impulse circuit is opened and the talking circuit is established. When the conversation is completed 70 and the calling station receiver is replaced on the switchhook the circuit is released and the switches are restored to normal.

Having now outlined the system and its 75 operation in a general manner, the method 80 of establishing a connection between stations 200 and 100, which may be in the same or separate exchanges depending upon the code number of the station called, will be described in detail.

Regular call.

When the receiver at station 200 (Fig. 2) is removed from the switchhook line relay 204 operates. Relay 210 then operates over 90 a circuit including a contact of relay 241 and brush 208 of the line finder switch LF. It should be understood that the brushes 205 to 208 inclusive move together under control of the stepping magnet 209 in the manner hereinafter described, and that these brushes in normal position rest upon the normal terminals as shown in Fig. 2. It should be noted that the conductor 251 is connected to the front contact of all other line relays in the same group as the line relay 204 so that the circuit to operate relay 210 will be closed regardless of which particular line relay in the group is operated. It should also be noted that the back contact of each line relay is connected to a terminal in the arc with which the brush 208 is associated. Relay 210 in operating closes a circuit to 100 105

operate the stepping magnet 209 by way of brush 208 and the front contact of relay 204. The stepping magnet 209 opens its own operating path and releases, causing the brushes 5 205 to 208 inclusive of the switch LF to rotate one step in a clock-wise direction. Brush 208 is so constructed as to bridge two adjacent terminals in the arc in rotating, but to make contact on one terminal only when 10 centered, thus preventing relay 210 from releasing during hunting until the brushes are centered on the terminals of the calling line. Assuming that the brushes 205 to 208 are 15 now resting upon a non-calling line, its associated line relay will not be operated and will supply a ground to again operate the stepping magnet 209 and advance the brushes of the switch LF to the terminals of the next line in the bank, when the stepping magnet 20 209 releases. Assuming these terminals are associated with the station 200 the line relay 204 which is operated will prevent ground being supplied to the brush 208, hence the relay 210 will release thus preventing the 25 stepping magnet 209 from reoperating. Relay 210, in releasing, closes a circuit by way of brush 207, to operate relays 203 and 241 in series, thus releasing the line relay 204 and preventing the relay 210 from reoperating.

With the brushes 205 and 206 of the line finder switch LF resting upon the terminals associated with station 200, the line is extended to operate relay 111 of the selector 35 S under control of relays 110, 114, and 117, by way of leads 227 and 228. Relay 111 operates relay 112, and the latter in turn operates relay 113 both over obvious circuits. Relay 241 operated, closes a circuit to operate relay 222 under control of relays 223, 241, 40 242, and brush 218 of the trunk finder TF in its normal position. Relay 222 operated, closes a circuit to operate the stepping magnet 219 under control of brush 218, and relays 241 and 242. It should be noted that the lead 252 connected to one of the forward contacts of relay 241 is strapped to one of the forward contacts of all similar relays in the group of trunk finder circuits, so that relay 222 and stepping magnet 219 will operate whenever relay 241 or some other similar relay operates. It should also be noted that with relay 241 operated, ground will be connected to every terminal of the arc associated 45 with brush 218 except the terminal corresponding to the trunk 227, 228 connected to line finder LF.

The stepping magnet 219 operated, opens its own operating circuit and releases, thus 50 advancing the brushes 211 to 218 inclusive of the trunk finder switch TF from the normal position to the terminals associated with the first line finder in the group.

Since this is not the line finder circuit sought, ground will be connected to brush

218 by way of the relays in the first line finder circuit corresponding to relays 241 and 242, hence the stepping magnet 219 will reoperate and upon releasing advance the brushes 211 to 218 inclusive of the trunk 55 finder switch TF to the terminals associated with the next line finder in the group, which we will assume to be the one sought. Brush 218 is constructed so as to bridge two adjacent terminals in the arc in rotating, but to make contact on one terminal only when 60 centered, thus preventing relay 222 from releasing during hunting until the brushes are centered on the terminals of the desired circuit. When the brush 218 rests on the 65 terminal associated with the desired circuit, which terminal is free from ground, relay 222 will release thus closing a circuit controlled by relays 222 and 241 by way of brush 217 to operate relays 223 and 242 in series. The operation of relay 242 causes the line finder circuit to test busy to all other trunk finder circuits, the operation of relay 223 prevents relay 222 from reoperating, and the release of relay 222 prevents the 70 stepping magnet 219 from advancing the brushes off the terminals associated with the line finder circuit LF. The operation of relay 223 operates relay 233 over an obvious circuit and closes parallel circuits to operate 75 relays 114 and 117 of the repeater R (Fig. 1), by way of lead 226 and brush 214. Relay 233 operated, operates relay 232 over an obvious circuit, and relay 114 prepares the 80 impulse circuit under control of armature 85 125 of relay 115 thus preventing relay 111 from releasing when relay 117 operates and prepares the operating circuit for relay 236 hereinafter described.

Relay 233 operated, closes a circuit to the 105 source of alternating current supply 234 to operate relay 236 as follows: 234, 216, 231, 119, 120, 121, 227, 205, 202, 201, 200, 202, 206, 228, 122, 123, 124, 230, 215, 236 to ground. Relay 117 operated closes a circuit to ground to operate relay 116 under control of relay 241, by way of lead 225. Relay 116 operated locks to ground under control of relay 241.

The circuit is now ready to receive the 115 first series of impulses produced by the substation dial 201. The dial 201 is now operated and released and as it returns to normal the loop of station 200 is momentarily opened by the impulse contacts (not shown) 120 of the dial 201. Relay 236 which is a very fast alternating current relay releases and closes its contacts 235, thereby completing the circuit to operate relay 237 under control of relays 232 and 223, and a parallel circuit to operate relay 115 by way of leads 126 and 229 and brush 213, also under control of relays 232 and 223.

Relay 237 closes an obvious circuit to operate the stepping magnet 221 of the trunk 130

finder TF sequence switch which includes brushes 243 and 220, while relay 115 being operated opens the holding circuit of the impulse relay 111 which closes the usual circuit (not shown) to cause the selector S to step in the usual manner, well known in the art. When the impulse springs of the dial 201 again close, relay 236 reoperates, and opens the circuits of relays 237 and 115. 5 Relay 237 being slow to release remains operated throughout the impulse period, but relay 115 releases thus reoperating relay 111. Each time relay 236 releases, relay 115 operates and relay 111 releases, thus repeating 10 the impulse from the dial circuit to the impulse relay 111 of the selector S. When the impulses corresponding to the first digit cease relays 115 and 237 both release, the former thus holding impulse relay 111 operated 15 as before, while the latter releases stepping magnet 221 thus advancing the brushes 238 and 243 to the next terminal in their respective arcs. At the end of the train of impulses, the selector S hunts in a manner particularly shown and described 20 in said patent, and selects an idle selector which we will assume to be the selector S¹. Relay 110 now operates, releasing relays 111 and 112 and extending the impulse path controlled 25 by relay 115 by way of brushes 109 and the terminals 108 to the impulse relay (not shown) of the selector S¹, and the holding ground previously supplied by relay 112 to operate relay 113, is replaced by a ground connected to lead 127 in the manner shown in said patent. The dial 201 is again operated and released for the next digit and relays 236, 115 and 237, and stepping magnet 221, function as previously described. 30 Relay 115 now controls the circuit of the impulse relay (not shown) of the selector S¹, causing the selector S¹ to function in a similar manner to the selector S. At the end of this train of impulses relays 35 236, 237, and 115, stepping magnet 221, and brush 220, function in the same manner as at the end of the first impulse train, and we will assume that the impulse circuit is extended to the connector C by way of the 40 brushes 107 and terminals 106, in which case relays 104 and 105 will operate, and the final impulsive circuit to relay 104 is now established under control of relay 115. The holding ground is now supplied from the connector relay 105 in the manner shown 45 in said patent.

When the third digit is dialed at station 200, relay 237 operates the stepping magnet 221 which upon releasing steps the brush 220 to the next terminal of the arc 238, and after the final digit is dialed the brush 220 comes to rest upon the terminal 239 of arc 238. During these operations and until disconnection takes place the ground to keep 50 relay 113 operated is supplied by relay 105.

We will assume that the brushes 102 finally come to rest upon the terminals 101 of the called line 100, that relay 103 operates, the called line 100 is signalled, and the party answers by removing the receiver from the switchhook, all of which is shown and described in detail in said patent.

When the brush 220 of the stepping magnet 221 comes to rest upon the terminal 239 of arc 238, an obvious circuit to operate the stepping magnet 219 is closed by way of brush 212 and lead 246, and the brushes 211 to 218 inclusive are restored to the normal position of the trunk finder switch TF. When brush 217 steps off terminal 247 the circuit through relays 242 and 223 is opened, releasing these relays. Relay 223 released, releases relays 115, 233 and 237. Relay 233 releases relays 232 and 236. When brush 214 steps off terminal 248, the circuit through relays 114 and 117 is opened, releasing these relays and establishing the transmission circuit, by extending leads 227 and 228 through to the brushes 102 of the connector C, thence to the called station 100. With the trunk finder switch TF in its normal position a circuit is closed to operate the stepping magnet 221 by way of brushes 243 and 211 to ground on the terminal 244, thus restoring this switch to normal.

Disconnection.

When the conversation is completed the receiver is replaced on the switchhook of station 200 thus releasing relay 104, which in turn releases relay 105. Relay 105 released removes the holding circuit for cut off relay 103, and the holding relays of the switches, and releases relays 110 and 113. Relay 113 closes a circuit to operate the stepping magnet 209 of the line finder switch LF under control of relays 114 and 116 by way of lead 224.

Stepping magnet 209 operated, opens its own operating circuit and releases, thus stepping the brushes 205 to 208 of the switch LF from the terminals associated with the line 200. When the brush 207 steps off the terminal 249, cut off relay 203 and relay 241 release, the former thus restoring line 200 to normal, and the latter closing a circuit to operate relay 210 by way of brush 208 and the terminal 250 which will be grounded under control of the line relay (not shown) associated with the line connected to terminal 250. The stepping magnet 209 reoperates and releases thus stepping the brushes 205 to 208 of the switch LF to the terminals of the next line of the group. This cycle of operations continues until brushes 205 to 208 either find another calling line, in which case the new call is established in the manner hereinbefore described, or the switch returns to normal, that is, the brushes of the line finder LF may be constructed as shown

in the drawing so that when one set of tips of the brushes leave the terminals of the last line in the banks another set of tips of these brushes will land on the first set of terminals in these banks. It is clear, therefore, that when the brush 208 lands on the first terminal of the corresponding bank, no ground will be found thereat and consequently relay 210 will release to open the circuit for 10 stepping magnet 209 and stop the switch.

Call abandoned before calling line is found.

Should the receiver at the station 200 be removed from the switchhook long enough 15 for the stepping magnet 209 to operate once, the brushes 205 to 208 inclusive of the switch LF will step to the terminals of the first line of the group. The release of relay 204 will cause the line 200 to test busy, and relay 20 210 will remain operated, and the stepping magnet 209 will step until the brushes 205 to 208 of the switch LF return to normal.

Call abandoned before a repeater circuit is 25 found.

When the receiver at station 200 is removed from the switchhook the stepping magnet 209 will step the brushes 205 to 208 inclusive to the terminals of the calling line, 30 and relays 111 and 241 will operate in the manner previously described under "Regular call". The stepping magnet 219 of the switch TF also will function, and relays 242 and 223 will operate in the manner previously 35 described. When the call is abandoned, relay 111 of the selector S will release, releasing relay 112, which will release relay 113. A circuit is now closed to operate the stepping magnet 209 of the switch LF under 40 control of relays 113 and 242, by way of leads 118 and 245. The stepping magnet 209 restores the line finder switch LF to normal in the manner previously described under "Disconnection". Relay 222 recuperates when 45 relays 223 and 241 release, and the circuit to operate the stepping magnet 219 and restore the trunk finder switch TF to normal is closed by way of brush 218.

Call abandoned before dialing is commenced.

If the call is abandoned after the repeater circuit is found but before dialing, the line finder and trunk finder switches are restored to normal in the manner described in the 55 last paragraph.

Call abandoned during dialing.

During the dialing period relay 116 is 60 operated and locked under control of relay 241 hence if at any time during dialing the call is abandoned relay 113 will release and close the circuit under control of relays 114 and 116 to operate the stepping magnet 209 by way of lead 224, thus releasing relays 241 and 203 and restoring the line finder switch 65

LF to normal in the manner previously described under "Regular call". Relay 241 released releases relays 242 and 223, and relay 222 reoperates and closes the circuit to operate the stepping magnet 219 and restore the trunk finder switch TF to normal under control of relays 222, 241 and 242 by way of brush 218.

Call abandoned after dialing is completed. 75

The circuit is restored to normal in the manner previously described under "Regular call".

What is claimed is:

1. A telephone system comprising a calling line equipped with a calling device, a called line, automatic switching apparatus at an intermediate point for interconnecting the calling and called lines, an alternating current source at an intermediate point, repeating means controlled by impulses produced by interruptions of current from said source by said calling device for transmitting for each alternating current impulse received by said repeating means a direct current impulse and means for setting said automatic switching apparatus under control of said direct current impulses. 80

2. A telephone system comprising a calling line equipped with a calling device, a called line, automatic switching apparatus at an intermediate point for interconnecting the calling and called lines, an alternating current source at an intermediate point, means for connecting said source to the calling line operated when the calling line is taken for use, repeating means controlled by impulses produced by interruptions of current from said source by said calling device for transmitting for each alternating current impulse received by said repeating means a direct current impulse and means for setting said automatic switching apparatus under control of said direct current impulses. 95

3. A telephone system comprising a calling line equipped with a calling device, a called line, automatic switching apparatus at an intermediate point for interconnecting the calling and called line, a high frequency alternating current source at an intermediate point, repeating means controlled by impulses produced by interruptions of current from said source by said calling device for transmitting for each alternating current impulse received by said repeating means a direct current impulse and means for setting said automatic switch apparatus under control of said direct current impulses. 110

4. In a telephone system, a central office, telephone lines terminating thereat, calling dials at the stations of said lines, selectors, non-numerical switches for extending calling lines to said selectors, a trunk finder, 120

- means actuated upon the initiation of a call for setting the finder in motion to connect with a selector taken for use by a calling line, a source of alternating current and an alternating current impulse relay associated with said trunk finder, an impulse circuit for said relay including said source, said trunk finder, said non-numerical switch and the calling line including the dial, and a second impulse circuit for controlling said 5 selectors and including a source of direct current and a direct current impulse relay said second circuit being directly controlled by the alternating current relay so that for each alternating current impulse received a corresponding direct current impulse is produced for the corresponding portion of said current relay and means for restoring said trunk finder upon the selection of the called line, whereby it reverts to common use. 35
6. In a telephone system, a central office, a telephone line, a selector at the central office for association with said line, a source of high frequency current and an alternating current relay at said central office, an interrupter in said telephone line, an impulse 40 circuit including said source, said relay, said interrupter and the conductors of said line, a second circuit into which impulses are repeated by said alternating current relay and including a source of direct current, an impulse relay for setting said selector and a contact of said alternating current relay and a switching means for disconnecting said sources of high frequency current and alternating current responsive to the reception of a certain number of series of impulses and means operative in response to such disconnection for connecting the selector with said conductors. 45
5. In a telephone system, a central office, telephone lines terminating thereat, calling dials at the stations of said lines, selectors and connectors, non-numerical switches for extending calling lines to said selectors, a trunk finder, means actuated upon the initiation of a call for setting the finder in motion to connect with a selector taken for use by a calling line, a source of alternating current and an alternating current impulse relay associated with said trunk finder, an impulse circuit for said relay including said 20 source, said trunk finder, said non-numerical switch and the calling line including its dial, a second impulse circuit for controlling said selectors and connector and including 25
- 30

In witness whereof, I hereunto subscribe my name this 4th day of September A. D., 1923.

RAY S. WILBUR.
